(57) **CLAIM**

The ornamental design for a baby monitoring apparatus, as shown and described.

DESCRIPTION

FIG. 1 is a front, top perspective view of a baby monitoring apparatus, showing my new design;

FIG. 2 is a rear, bottom perspective view thereof;

FIG. 3 is a front, top perspective view of the camera of the baby monitoring apparatus shown in FIG. 1;

FIG. 4 is a rear, bottom perspective view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof;

FIG. 10 is a bottom plan view thereof;

FIG. 11 is a front, top perspective view of the tablet of the baby monitoring apparatus shown in FIG. 1;

FIG. 12 is a rear, bottom perspective view thereof;

FIG. 13 is a front elevation view thereof;

FIG. 14 is a rear elevation view thereof;

FIG. 15 is a left side elevation view thereof;

FIG. 16 is a right side elevation view thereof;

FIG. 17 is a top plan view thereof;

FIG. 18 is a bottom plan view thereof;

FIG. 19 is another perspective view thereof, shown in an alternative position;

FIG. 20 is an enlarged portion view taken from encircled portion labeled, "20," in FIG. 1;

FIG. 21 is an enlarged portion view taken from encircled portion labeled, "21," in FIG. 1;

FIG. 22 is an enlarged portion view taken from encircled portion labeled, "22," in FIG. 1;

FIG. 23 is an enlarged portion view taken from encircled portion labeled, "23," in FIG. 2;

FIG. 24 is an enlarged portion view taken from encircled portion labeled, "24," in FIG. 7;

FIG. 25 is an enlarged portion view taken from encircled portion labeled, "25," in FIG. 8;

(Continued)

FIG. 26 is an enlarged portion view taken from encircled portion labeled, "26," in FIG. 9;

FIG. 27 is an enlarged portion view taken from encircled portion labeled, "27," in FIG. 10;

FIG. 28 is an enlarged portion view taken from encircled portion labeled, "28," in FIG. 15;

FIG. 29 is an enlarged portion view taken from encircled portion labeled, "29," in FIG. 17; and,

FIG. 30 is an enlarged portion view taken from encircled portion labeled, "30," in FIG. 18.

The dash-dash broken lines in the figures illustrate portions of the baby monitoring apparatus that form no part of the claimed design. The dash-dot-dash broken lines in FIGS. 1, 2, 7-10, 15, 17-18 and 20-30 depict the bounds of the enlarged views and form no part of the claimed design.
